US00D919219S

(12) **United States Design Patent** (10) Patent No.: **US D919,219 S**
(45) Date of Patent: **** May 11, 2021**

(54) **COLLAPSIBLE TRASH CAN**

(71) Applicant: **Honey-Can-Do International, LLC**,
Berkeley, IL (US)

(72) Inventors: **Steven Greenspon**, Burr Ridge, IL
(US); **Valerie Snow**, Chicago, IL (US);
Kristina Tarasova, Oak Park, IL (US)

(73) Assignee: **Honey-Can-Do International, LLC**,
Berkeley, IL (US)

(**) Term: **15 Years**

(21) Appl. No.: **29/714,370**

(22) Filed: **Nov. 22, 2019**

(51) LOC (13) Cl. **09-09**

(52) U.S. Cl.

USPC **D34/1; D7/512**

(58) **Field of Classification Search**

USPC D34/1, 10, 11; D9/683; D7/532, 612,
D7/512; D11/152; D19/85

Much Shelist, P.C.

(57) **CLAIM**

The collapsible trash can, as shown and described.

DESCRIPTION

FIG. 1 is a front perspective view showing the new design for a collapsible trash can in the expanded position;

FIG. 2 is a front left side perspective view thereof;

FIG. 3 is a front perspective view thereof, taken from underneath the collapsible trash can;

FIG. 4 is a front left side perspective view thereof, taken from underneath the collapsible trash can;

FIG. 5 is a front view thereof, the rear view being a mirror image thereof;

FIG. 6 is a left side view thereof, the right side view being a mirror image thereof;

FIG. 7 is a top plan view thereof;

FIG. 8 is a bottom plan view thereof;

FIG. 9 is a front perspective view thereof, taken from above collapsible trash can;

FIG. 10 is a front perspective view showing the new design for a collapsible trash can in the collapsed position;

FIG. 11 is a front left side perspective view thereof;

FIG. 12 is a front perspective view thereof, taken from underneath the collapsible trash can;

FIG. 13 is a front left side perspective view thereof, taken from underneath the collapsible trash can;

FIG. 14 is a front view thereof, the rear view being a mirror image thereof;

FIG. 15 is a left side view thereof, the right side view being a mirror image thereof;

FIG. 16 is a top plan view thereof;

FIG. 17 is a bottom plan view thereof; and,

FIG. 18 is a front perspective view thereof, taken from above collapsible trash can.
